UNITED STATES PATENT OFFICE.

PAUL HEINRICH ERNST RÖMER AND MORITZ PAUL MEISSNER, OF CHEMNITZ,
SAXONY, GERMANY, ASSIGNORS TO (THE FIRM) C. H. WEISBACH, OF
SAME PLACE.

MACHINE FOR FOLDING FABRICS AND INSERTING PRESSING-BOARDS BETWEEN THE FOLDS THEREOF.

SPECIFICATION forming part of Letters Patent No. 296,067, dated April 1, 1884.

Application filed January 25, 1883. (No model.)

To all whom it may concern:

Be it known that we, PAUL HEINRICH ERNST RÖMER and MORITZ PAUL MEISSNER, of Chemnitz, in the Kingdom of Saxony, German Empire, have invented a new and useful Improvement in Machines for Automatically Folding Fabrics and Inserting Pressing - Boards Between the Folds thereof; and the following is declared to be a full and exact description of the same.

This invention relates to the machine in which pressing - boards, pressing - paper, or cards are automatically inserted between the folds of fabric. For this purpose a table is arranged which is kept in its highest position by a spring, and which table descends in proportion to the weight of fabric and pressing-boards with which it becomes loaded. Above this table two rollers travel, working in horizontal guides arranged above the table and near the sides of the same. Between these rollers the fabric enters, which is spread over the table into regularly-arranged folds by the traveling rollers. There are two sets of pinchers arranged in combination with the above-mentioned rollers and traveling with them, which pinchers are opened and closed at proper intervals. At each change in the direction of travel of said rollers one pair of pinchers is closed and seizes or takes hold of a pressing-board, drawing the same along with it. As the travel of the rollers is completed in one direction, the same pair of pinchers is opened, thereby releasing the pressing-board, which is deposited upon the fabric. At the same time the other pair of pinchers at the other side of the rollers is closed, in order to take hold of another pressing-board at the other side of the machine, drawing the board over the newly-laid fold of fabric and releasing and depositing the same at the end of the movement. This operation is carried on continuously while the machine is in operation, a pressing-board being taken from alternate sides and deposited on the fabric. The pressing-boards are arranged at both sides of the machine within sliding boxes. These boxes preferably run upon rails. The sides of these

boxes facing the machine are open, to allow the box to be moved toward one or more pressing-rollers, against which the pressing-boards come into contact, and are kept in a vertical position by such rollers. With each box a mechanism is combined by which a pressing-board at the proper instant is raised and pushed into a curved guide, thereby changing its path or movement from perpendicular to horizontal, and the board being held is ready for its protruding end to be seized by the above-mentioned pinchers at the proper instant and be drawn out of the curved guide and deposited upon the last-laid fold of fabric.

The machine is represented in side view (partly in section) in Fig. 1 and in plan in Fig. 2. The other figures show the details, and are separately referred to.

a is the table, carried by a central rod, *b*, which may ascend or descend within a tubular column, *b*³, so that the table supported by a spiral spring, *b*⁴, may descend according to the weight of the fabric and boards deposited thereon. Above the table *a* and at both sides of it two horizontal guides, *a*³, are arranged, in which two rollers, *f f'*, travel, which fold the fabric on the table *a*. The entrance of the fabric between such rollers is indicated by the vertical arrow, Fig. 1. The rollers are mounted in end bearings that are common to both, which bearings are moved by the lever *c*, which is slotted at the upper end, and is moved by the rod *d*, to which motion is imparted by the crank *e*. The lever *c* has its fulcrum *c*² at its lower end.

The arrangement, construction, and mode of working of the two sets of pinchers at both sides of the rollers *f f'* are more clearly to be seen in the partial section, Fig. 3, and plan, Fig. 4. It is supposed that in the position illustrated the parts travel in the direction of the arrow, Fig. 3, so that the left-hand-side pinchers are closed and draw along a pressing-board, while the right-hand-side pinchers are open, and will be closed at the completion of this movement in order to seize a pressing-board. The end bearings that slide in the

guides a^3 are connected by the cross-bars b' . Upon each of these bars b' there are two jaws, one near each end of the bar and projecting outwardly, so as to be adapted to grasp and draw into place the boards from first one end of the machine and then the other. The respective jaws are alike and operate together in pairs, the parts standing in opposite positions at the respective ends of the shaft. We will describe one jaw and the mechanism connected with it.

Upon the bar b' there is a fixed jaw, a' , that projects therefrom nearly horizontally. To this fixed jaw is hinged the moving jaw c' , that is made as a bent lever, the moving jaw c' extending horizontally beneath the jaw a' , the other portion or lever end, c' , standing nearly vertically. There is a spring, d' , above the fixed jaw a' , the upper part of which spring acts against the vertical portion c' of the moving jaw c' , tending to close the same. When the board is grasped by the jaws, the pressure of the spring d' causes such jaws to retain their hold of such board until it is drawn entirely over the layer of fabric. At this moment the jaw is opened by the following means: The rocker-shaft k is above the bar b' , and has at one end a finger, h , that is acted upon by the spring-bolt l or l' as the carriage is moved, and this finger h turns the rocker-shaft k , and by the cam i opens the moving jaw c' by pressing against the back of the lever end c' . The spring around the spring-bolt l or l' allows it to rise if the end of the finger h comes in contact with the inclined end of the spring-bolt l or l' on the return movement. There is a spring-bolt, e' , that is supported in bearings on the bar b' , and it has an arm at its end which is adjacent to the back of the lever end c' of the moving jaw c' . When this moving jaw is opened by the cam i , rocker-shaft k , finger h , and spring-bolt l or l' , as aforesaid, the spring of the bolt e' gives it an endwise movement and brings the arm at its end in behind the lever end c' of the moving jaw c' , so as to hold that jaw open, and it remains in that position until the carriage and bars b have nearly reached the extreme of their movement in the opposite direction, at which time the open jaw has reached the end of the board that is to be drawn in. At this moment the end of the bolt e' runs against the incline g or g' , and its arm is carried from behind the lever end c' of the open moving jaw c' and liberates such jaw, so that the spring d' closes and the pinchers grasp the board and move it with the carriage, as aforesaid. Each closing of one pair of pinchers has for its result the seizing of a press-board, while the opening of that device deposits a press-board on the fabric. The boards are vertically arranged within the boxes m , running on wheels r^4 and rails r^5 . The boxes are pressed toward the middle of the machine by the weights m' , so that the pressing-boards always bear against the roller n . The upper part of the

boards bear in the same manner against the friction-disks o . If these friction-disks o are turned or revolved by means of the bevel-wheels p p' , they will by friction cause the pressing-boards in contact with them to rise a certain distance, and at the same time the horizontal rod r will come underneath the lower edge of the board raised. The rod r is suspended by cords that pass over the rollers u , and are attached to the upper ends of the levers t . The lower ends of these levers t are connected with the shaft t' , and this shaft is rocked and the rod r drawn upwardly at the proper time to lift the board and cause its upper end to enter into and pass through the bent or curved guide v , so that the board protrudes from the guide with its end horizontal, and may be seized by the pinchers at the proper instant. The pressing-board by this movement is changed from a perpendicular to a horizontal position. The levers s and s' are connected to the horizontal rock-shaft t' , and receive their motion from the cams r' r'' , upon which the arms o' and o'' rest.

Fig. 5 indicates on a larger scale the curved guide v , through which the pressing-boards are transmitted from a vertical position into a horizontal one.

We claim as our invention—

1. The combination, with the table which is adapted to descend by the weight of fabric upon it, of the traveling rollers and pinchers, the movable vertical side boxes containing the pressing-boards, constructed so as to support or carry the pressing-boards in a vertical position, and mechanism for operating said pinchers, and for raising said boards automatically and alternately from the vertical boxes, and for changing their position from a vertical to a horizontal one in order to be seized by the pinchers, substantially as set forth.

2. The combination, with the table for the fabric, the traveling carriage and rollers, and means, substantially as described, for moving the same, of the pinchers composed of fixed and moving jaws, the bars b' , springs d' , bolts e' , fingers h , cam-shaped arms i , rocker-shaft k , spring-studs l l' , and cams g g' , whereby the pinchers are alternately opened and shut and the sheets of pressing-board alternately grasped and deposited, substantially as set forth.

3. The combination, with the boxes m , for holding the pressing-boards, the weights for moving the same, and the ways upon which said boxes are supported, of the rollers n , disks o , bevel-wheels p p' , rods r , the levers s and t , and means, substantially as described, for operating the same, whereby the sheets of pressing-board are raised and delivered, substantially as set forth.

4. The combination, with the vertical boxes for holding the pressing-boards, constructed so as to support or carry the pressing-boards in a vertical position, and means, substantially as described, for raising and delivering said

pressing-boards, of the curved guide *v*, through which the boards are transmitted from a perpendicular to a horizontal position, and means, substantially as set forth, for grasping said boards, conveying them forward, and depositing them upon the fabric, as set forth.

5 In testimony whereof we have hereunto set

our hands, this 7th day of December, 1882, in the presence of two subscribing witnesses.
